UNITED STATES PATENT OFFICE

EDGAR A. BARNARD, OF WASHINGTON, DISTRICT OF COLUMBIA

DESIGN FOR A LAMP

Application filed March 1, 1932. Serial No. 43,046. Term of patent 3½ years.

To all whom it may concern:

Be it known that I, EDGAR A. BARNARD, a citizen of the United States, residing at Washington, in the District of Columbia, have invented a new, original, and ornamental Design for a Lamp, of which the following is a specification, reference being had to the accompanying drawings, forming part thereof.

I claim:

The ornamental design for a lamp as shown.

EDGAR A. BARNARD.
